US0D1105729S

(12) **United States Design Patent** (10) Patent No.: **US D1,105,729 S**
(45) Date of Patent: ** Dec. 16, 2025

(54) **FOOTWEAR ARTICLE**

(71) Applicant: **Amer Sports Canada Inc.**, North Vancouver (CA)

(72) Inventors: **Christopher Pope**, Portland, OR (US); **Erik Arlen**, Paris (FR); **Tanguy Bothier**, Paris (FR)

(73) Assignee: **Amer Sports Canada Inc.**, North Vancouver (CA)

(**) Term: **15 Years**

(21) Appl. No.: **29/931,919**

(22) Filed: **Mar. 11, 2024**

(51) LOC (15) Cl. **02-04**

(52) U.S. Cl.

USPC **D2/969**; D2/896

(58) **Field of Classification Search**

USPC D2/896-900, 909-912, 920, 943, 944, D2/946, 951-958, 969, 970-974

CPC A43B 23/07; A43B 3/16; A43B 23/00; A43B 23/02; A43B 5/04; A43B 3/02

(57) **CLAIM**

The ornamental design for a footwear article, as shown and described.

DESCRIPTION

FIG. 1 is a front, side perspective view of a footwear article;

FIG. 2 is a front view thereof;

FIG. 3 is a rear view thereof;

FIG. 4 is a first side view thereof;

FIG. 5 is a second side view thereof; and,

FIG. 6 is a top view thereof.

The broken lines depict portions of the footwear article that form no part of the claimed design.

1 Claim, 5 Drawing Sheets
